UNITED STATES PATENT OFFICE.

JOHN W. MARLEY, OF CHICAGO, ILLINOIS.

ELECTRO-MAGNETIC CAR-SIGNAL.

SPECIFICATION forming part of Letters Patent No. 271,882, dated February 6, 1883.

Application filed September 6, 1882. (No model.)

To all whom it may concern:

Be it known that I, JOHN WESLEY MARLEY, M. D., of Chicago, in the county of Cook and State of Illinois, have invented new and useful Improvements in Electro-Magnets for Locomotives and other Purposes, of which the following is a specification, reference being had to the accompanying drawings, illustrating the improvement.

- 10. The object of the present invention is to provide means which will automatically indicate to the engineer that the train must be stopped at any point between two stations to avoid accident, and to provide better means for the person having charge of the train to communicate with a front or rear station agent for the greater safety of moving trains of cars. This I accomplish by electro-magnets placed at such intervals between stations as deemed most 15 practicable, and connecting these magnets with the telegraph-wire, so that the armature of any one electro-magnet between two stations may be so set from either station that a trip-bar on the engine will come in contact with 20 a trigger on the armature, and be so moved (where the train is moving in either direction) that an apparatus on the engine or locomotive will sound the alarm for the train to be stopped and the armature be so reset as to permit 25 trains to pass and repass without the alarm being sounded, as the whole in detail is fully shown and described.

Referring to the figures in the drawings, Figure 1 is a side skeleton view of a locomotive-engine carrying the alarm apparatus; Fig. 2, a top or plan view of one-half of the pilot to which the trip-bar is attached; Fig. 3, an end elevation of the magnet-box and magnets therein, looking in the direction of arrow, Fig. 1. 30 A represents an ordinary locomotive-engine; C, the cab, and B the pilot thereto.

N is the railroad-track.

D represents a suitable box to contain the ordinary electro-magnets, E E. This box is rigidly attached to one or more rails of the track, so as always to be in the same relative vertical position thereto.

Rigidly connected with the box D is a strong vertical guide, d, through which a trigger, e 45 passes, and is permitted to have a free vertical reciprocating movement. The lower end

of this trigger is pivoted to a slotted eye, b, on the end of the armature f, and on the upper end is formed a cam, F, the contact of which with the trip-bar e on the pilot B will give the alarm to the engineer, as after this stated. This trip-bar is pivoted to the pilot-frame, so as to lie about one and one-half inch above the rail N, so that it swings in a horizontal plane, and to insure its always lying at right angles to the rail when not acted on, a coil-spring, m, is attached to the trip-bar at its inner end, and to the pilot, as shown at Fig. 2. The inner end of the trip-bar supports a stud, n, to which an end of a rod, G, is jointed. This rod passes back through eyes S S, and is jointed to an elbow-lever, H, which is pivoted to the cab at r. The rear end of this elbow-lever, by means of a suitable joint, supports a vertical rod, I, which has a guide in a sleeve, J, attached to an elbow-rod, 1. This rod is pivoted to the cab or other suitable support at 3, and to prevent it from getting out of position a stop, 2, is placed below it.

Above the sleeve J is placed a lug, 4, and above the elbow-rod 1 is hung a bell-hammer, 6, to operate on a bell, 9. To prevent the bell-hammer from coming in contact with the rods I 1 when not in use, a stop, 7, is placed below it, as shown at Fig. 1. This construction is such that the alarm will be given when the engine moves either backward or forward. For example, when the engine is moving forward the trip-bar e will be thrown back by coming in contact with the cam F on the trigger 85 e, and consequently draw forward the rod G, draw down the rod I, and by means of the lug 4 on the rod and sleeve turn the elbow-rod 1 so as to bring its vertical part against the bell-hammer, and as a result the alarm will be 90 sounded from the bell 9. Should the engine be run backward, the rod G will be drawn toward the pilot B and the rod I will strike the bell-hammer.

The boxes D are to be located at suitable 95 places between stations, that the station agent may stop a train should it become necessary.

The real merit of this invention, from the following, will be fully comprehended: Suppose stations A and B are twenty miles apart, and between the stations were four electric alarms on the plan described, four miles apart, and a

- train should meet with an accident seven miles from station A at about the time a train passes station B. Now, the conductor on the train which met with an accident can connect a wire 5 with the main line in the ordinary manner of reporting in such cases and notify the agent at B of the condition of affairs with his train, and the operator at station B could have the connection broken at A, and then bring all the 10 armatures *f* in the four boxes to the magnets, so as to elevate the cams *F* to positions so the trip-bar *e* on the engine of the train which left station B would come in contact with the cam F and alarm the engineer, so as to stop his train 15 before running into the train which left station A. Should it come to the knowledge of the station agent at station A or B that trains are approaching each other, he could set the alarm to stop both trains.
- 20 c The connecting of the magnets E with the main wire consists of a wire, L, which is cased in an iron tube, M, to a suitable height above the ground to insure protection. When the current is on, the armature will lie in the position shown at Fig. 1, and the cam F will be elevated to come in contact with the trip-bar *e*; but when the current is off, the trigger *c* F, by its gravity, will bring the armature down onto a bracket-stop, *a*, in which position the 25 cam F will be below the bar *e*.
- 30

In the foregoing I have shown and described mechanism to operate in combination with the electro-magnet, whereby a train of cars might be signaled; but I do not claim to have been the first to place a tripping device near the 35 rail, so as to put a signal apparatus in operation on the locomotive independent of the magnet, as such devices have been before used. I therefore confine my invention to signals where the electro-magnet is employed to hold the 40 trigger at the side of the rail up so as to come in contact with the trip-lever on the locomotive.

Having thus described my invention, what I claim, and desire to secure by Letters Patent 45 of the United States, is—

In railway-signals, the electro-magnets connected with the telegraph-wire L, in combination with the trigger *c* and its lever-connection with the magnets, to hold the trigger up 50 to come in contact with the trip-lever on the locomotive so as to put in operation an alarm apparatus on the locomotive, substantially as specified.

JOHN WESLEY MARLEY.
